UNITED STATES PATENT OFFICE

2,404,842

ALARM SYSTEM

John N. Hoekstra, Royal Oak, Mich.

Application September 23, 1944, Serial No. 555,532

4 Claims. (Cl. 179—5)

1

This invention relates to alarm systems the purpose being to provide a new and improved means for transmitting a message as by means of a telephone system in the case of a fire for instance.

A feature of the invention resides in the use of a strip of material having a groove formed therein similar to the groove in a phonograph record and by means of which a spoken message may be transmitted to a telephone circuit and is repeated at successive intervals.

These and other objects and features of the invention are hereinafter more fully described and claimed and which is shown in the accompanying drawing in which—

Fig. 1 is an illustration partly diagrammatic of the apparatus embodying my invention.

Fig. 2 is a cross section thereof at the point of contact of the needle with the groove.

Fig. 3 is a diagrammatic view showing the reels on which the tape is wound.

Fig. 4 is a similar view showing a somewhat different arrangement of parts.

Fig. 5 is a diagram showing means for causing operation of the apparatus.

The apparatus is usable in buildings where fires may occur and in the operation of the apparatus a spoken message is transmitted to the telephone station giving the location of the fire.

In the preferred arrangement of parts a strip 1 is formed with a longitudinal groove 2 and this portion of the strip is non-magnetic in character while the portion indicated at 4 and 5 is magnetic and the message is formed in the groove between these magnetic elements which serve to separate repeated messages, or to provide a time interval between differing messages.

The groove extending across the metallic elements as indicated at 2a is a straight line and the strip is sufficiently long to permit repeated messages on the portion 1 at successive intervals and the direction of movement of the strip is indicated by the arrow in each of Figs. 1, 3 and 4.

The apparatus consists of a permanent magnet 6 which may be mounted in any approved manner, as for instance by means of the arm 7 shown in Fig. 4, which is flexible in character. The weight of the magnet 6, as shown in Fig. 4, causes the same to normally occupy a position out of contact with the strip. The magnet however is sufficiently close to the strip to be attracted by the magnetic elements 4 and 5 and there may be one or more such strips and in fact may be of one piece of metal of the desired length. The magnet 6 has a stem 8 that nor-

2

mally extends into the mercury in the cup 9 and this mercury cup forms part of the electric circuit 10 which includes a coil 11 on the stylus 12 which rides the groove. When the magnet 6 is attracted by the metallic portions of the strip the stem 8 is moved out of contact with the mercury in the cup 9 as is indicated in Fig. 3 which is the normal position of the parts.

In Fig. 5 is shown a means for closing the circuit in the event of a fire. This consists of a bellows element 13 and a second bellows element 14 connected by a tube 15. The bellows elements and tube are filled with a fluid either gaseous or liquid and in the event of a fire a weight 16 is dropped which compresses the bellows 13 and expands the bellows 14 to contact with one end of the lever 17, the opposite end of which is provided with a brake shoe 18 normally held in surface contact with the surface 20 of the wound tape on the spool 19 and normally prevents rotation of the reel. The expansion of the bellows member 14 releases the brake carried on the end of the pivoted arm 17, and as the weight continues to rest on the bellows 13, the bellows 14 is maintained in expanded condition by the fluid therein and permits the reels to continue in rotation as long as the spring motor is operated. The supporting means for the bellows members may be of any approved form and is not 30 here shown.

While I have provided the strip 1 with grooves similar to that of a phonograph, the invention is not confined to such character of means for transmitting the message as it may consist of dots and dashes as in a telegraph system. Any type of message may be transmitted depending upon the character and requirement of any particular installation. The strip may be formed of a series of magnetic and non-magnetic elements so arranged as to transmit the desired information as by a dot and dash system used in telegraphy.

It will be noted that in Fig. 2 the strip 1 is supported by means of grooved wheels 21 and 22 45 as indicated in Fig. 2. These wheels are to be understood as being rotatably mounted on a supporting element (not here shown) in a manner tending to prevent lateral displacement of the strip adjacent the point of contact of the stylus 50 12 with the groove. The grooved wheel 21 may be mounted in a stationary member 23 while the wheel 22 may ride in a slot in the supporting member 24 and may be spring pressed to contact with the one edge of the strip 1 as by means of the spring 25 connected with the spindle of the 55

wheel 22 by a bar 26. This arrangement prevents lateral displacement of the strip 1. It is movement of the stylus in the coil 12 that causes fluctuation in the electric circuit in which the wires 10 and 10a are connected indicated at 11a and 11b in Figs. 1 and 4 and thereby causes fluctuation in the said lines and thence to a receiver (not here shown).

It is to be understood that the speed of movement of the strip having the groove corresponding to the groove in a phonograph record should correspond to the speed of movement of the phonograph record relative to the needle. The invention, however, is not confined to a groove similar to the phonograph groove as the groove may be so formed as to transmit a message similar to that of a telegraph recording tape.

It is believed evident from the foregoing description that the various features and objects of the invention are attained by the means herein disclosed. It is pointed out however that various changes may be made in the character and relationship of parts within the scope of the appended claims.

Having thus briefly described my invention, its utility and mode of operation, what I claim and desire to secure by Letters Patent of the United States is:

1. An alarm system for automatically transmitting a message to a telegraph or telephone circuit, comprising a tape of thin material formed of a series of sections of a desired length separated by sections of magnetic material, means by which the tape may be moved comprising a spring motor including a wheel like portion on which the tape may be wound, a brake means tending to hold the wheel portion from rotation, means for causing release of the reel to rotation by its motor whereby rotation thereof winds the tape thereon, said tape having magnetic and non-magnetic sections arranged end to end in a single strip, the non-magnetic sections having a groove in the face thereof similar to the groove of a phonograph record, a stylus for riding the groove, means whereby vibration of the stylus due to the character of the groove in the non-magnetic section causes a fluctuation in an electric circuit, means actuated by said magnetic sections tending to break the circuit to the telephone or telegraph system and providing an arrangement

whereby successive messages may be transmitted to a receiving station, means tending to normally maintain the motor reel stationary, and means whereby the reel may be released to rotation by the motor and thereby transmit the message to the telegraph or telephone circuit.

2. An alarm system comprising a tape formed of a thin strip of material formed of magnetic and non-magnetic sections, the non-magnetic sections of the tape having a groove in its surface similar to the groove of a phonograph record, a stylus for engaging the groove, a pair of reels in spaced relation on which the tape is wound, one of the reels being rotatable as by means of a coiled spring to thereby move the tape across the stylus, an electric system in which the stylus is connected to cause current fluctuation therein due to vibration of the stylus traversing the groove of the non-magnetic sections, and means including a magnet stationarily positioned adjacent the surface of the tape opposite that engaged by the stylus and adapted to break the circuit due to its being attracted by the magnetic portion of the tape.

25 3. In an alarm system, a tape formed of a thin strip of material having magnetic and non-magnetic sections in alternate relation, the non-magnetic sections having a groove in the surface thereof similar to the groove in a phonograph record, and the magnetic sections having a groove therein on a straight line connecting with the respective ends of the non-magnetic sections, and means whereby traverse of the groove by movement of the tape beneath the stylus transmits 30 successive messages to an electric circuit substantially as described.

4. In an alarm system, a tape having a groove in the surface thereof, means for causing movement of the tape, a stylus for riding the groove, an electric circuit in which the stylus is connected, a coil therein in which the stylus is positioned, the groove having successive spaced portions thereof of such form as to cause variations in the position of the stylus in the coil to thereby 40 cause fluctuation in the electric circuit and portions therebetween non-productive of current fluctuation whereby a message may be transmitted to the circuit at successive time intervals.

JOHN N. HOEKSTRA.
